SPROCKET FOR BICYCLES

Carl Payberg, Hollywood, and Walter H. Johnston,
Miami, Fla.

Application January 5, 1955, Serial No. 33,850

Term of patent 7 years

(Cl. D90—17)

FIG. 1.

FIG. 2.

Figure 1 is a side elevation of sprocket for bicycles, showing our new design, and

Figure 2 is an edge view thereof.

The dominant feature of our design resides in the full line portion of the drawing.

We claim:

The ornamental design for a sprocket for bicycles, as shown and described.
